UNITED STATES PATENT OFFICE.

JAMES C. JARDINE, JAMES DICKIE, AND GEORGE A. BOWNESS, OF SUMMERSIDE, PRINCE EDWARD ISLAND, CANADA.

CART-SADDLE.

1,328,922.

Specification of Letters Patent. Patented Jan. 27, 1920.

Application filed January 8, 1919. Serial No. 270,131.

To all whom it may concern:

Be it known that we, JAMES C. JARDINE, JAMES DICKIE, and GEORGE A. BOWNESS, all subjects of the King of Great Britain, 5 residing at Summerside, Prince Edward Island, Canada, have invented certain new and useful Improvements in Cart-Saddles; and we do hereby declare that the following is a full, clear, and exact description of the invention, such as will enable others skilled in the art to which it appertains to make and use the same.

The present invention relates to saddles and more particularly to a cart saddle for 15 connecting the harness to draft animals.

An object of the present invention is to provide a saddle of this character which consists of a plurality of interchangeable parts, so that should any one of the same 20 become worn or broken an unskilled person in the art of saddle making may easily and readily apply a new part to take place of this worn or broken part.

A further object of the present invention 25 is to provide a saddle of this character having its various parts detachable so as to eliminate the use of stitches for connecting the parts as has been heretofore done and also produce a saddle in which the life there- 30 of will be prolonged and one which will be commercially desirable.

With the above and other objects in view which will hereinafter appear as the description continues, the invention consists of 35 the novel features of construction, combination and formation of parts as will be hereinafter more fully described and particu- larly pointed out in the appended claim.

In the accompanying drawings:

40 Figure 1 is a perspective view of the saddle embodying the present invention; Fig. 2 is a front elevation of the same; Fig. 3 is a vertical section; Fig. 4 is a detail transverse section; and, 45 Fig. 5 is a detail vertical longitudinal section.

The invention will be best understood from a consideration of the following detailed description, taken in connection with 50 the accompanying drawings forming part of this specification, with the further understand- ing that while the drawings show a partial form of the invention, the latter is

not confined to any strict conformity with the showing of the drawings, but may be 55 changed and modified so long as such changes and modifications mark no material departure from the salient features of the invention.

Like and corresponding parts are indi- 60 cated by similar reference characters throughout the several views.

The numeral 1 indicates the saddletree which is semi-circular in configuration and has a groove in its upper face for the recep- 65 tion of the shaft supporting straps. The saddle also comprises two detachable sec- tions which may be made of leather, wood, iron, steel or similar material, one of which indicated by the numeral 2 is the cantle 70 section and the other one indicated by the numeral 3 is the pommel section which comprise the pad boards and adapted to be connected to the saddletree and pad boards are a pair of pads 4. These pads each com- 75 prise a backing 5 having secured thereto a leather facing 6 which forms a bracket for holding the padding material 7. This fac- ing 6 may be made of leather or any other suitable material and the inner faces of 80 the members 5 are reinforced by means of the metallic cross bars 8 each having threaded openings formed therein. Extending through the saddletree are the screw bolts 9 and these latter extend through the 85 backing 5 and the threaded openings ar- ranged within the plates 8 for detachably connecting the pads 4 to the saddletree and which also hold the pad boards 2 and 3 in place. The inner edges of these boards 90 2 and 3 rest within the recess 10 formed within the opposite sides adjacent the lower face of the saddletree and the boards 2 and 3 are connected to the backing plates 5 by means of the screws or similar fastening 95 members 11. The girth band comprises two sections indicated by the numerals 12 and 13 and these sections are detachably con- 100 nected together by means of the buckle 14, whereas their opposite ends are secured be- tween the pads and the saddletree.

From the foregoing it is obvious that we have produced a cart saddle comprising a plurality of detachable sections so that the various parts thereof may be manufactured 105 separately and readily assembled without

the aid of any one experienced in the art of saddle making, and it is to be further noted that should any one of the parts become worn or broken a new one may be easily and readily substituted therefor.

Having thus fully described our invention, what we claim as new and desire to secure by Letters Patent is:—

A saddle of the character described comprising a saddletree, a cantle section, a pommel section, a pair of pads, and means

for detachably connecting said pads to said saddletree, said pads adapted to retain said cantle and pommel sections adjacent said saddletree substantially as and for the purpose specified. 15

In witness whereof we have hereunto set our hands.

JAMES C. JARDINE.

JAMES DICKIE.

GEORGE A. BOWNESS.
